UNITED STATES PATENT OFFICE.

GEORGE P. REUHL, OF CINCINNATI, OHIO.

COATING-MACHINE.

No. 800,016.

Specification of Letters Patent.

Patented Sept. 19, 1905.

Application filed May 16, 1904. Serial No. 208,210.

To all whom it may concern:

Be it known that I, GEORGE P. REUHL, a citizen of the United States, residing at Cincinnati, in the county of Hamilton and State of Ohio, have invented certain new and useful Improvements in Coating-Machines, of which the following is a specification.

It is the object of my invention to provide a new and useful coating-machine adapted for applying a cover or coating in highly-divided state to stock passing through the machine.

In my improved device I provide a feeding-table upon which stock is fed, upon preferably both sides of which atomizing apparatus is arranged for playing upon the stock while being fed through the machine. The atomizing apparatus is preferably adjustable to height to angle with relation to the direction of the feed and to angle transversely of the stock, so that all parts of the stock may be subjected to the spraying while being fed, the tips of the atomizers being also preferably adjustable for permitting materials of different consistencies or composition to be projected therethrough.

My improved device is applicable for coating various substances with different coatings, and is especially applicable for finishing moldings, and I have shown my improved machine as applied for finishing picture-moldings.

My invention consists in the various combinations herein described and claimed; further, in providing a casing through which the stock to be operated on is arranged to pass and while passing therethrough providing it with its cover, coating, or finish by means of atomizing apparatus; further, in providing a casing in which stock is subjected to the action of atomizing apparatus and through which the stock is arranged to be propelled by feeding means located outside the casing; further, in providing atomizing apparatus at either side of the stock arranged to play upon the stock while passing through the casing, and, further, in the parts and in the construction, arrangement, and combinations of parts hereinafter more fully described and claimed.

In the drawings, Figure 1 is a side elevation of my improved device, partly broken away for better illustration of parts. Fig. 2 is a plan view of the same, partly broken away, and with the covering of the casing removed. Fig. 3 is a cross-section of the same on the line $\alpha\alpha$ of Fig. 2 with the frame partly broken away. Fig. 4 is a perspective

view of one of the atomizers. Fig. 5 is a section of the upper feeding device on the line yy of Fig. 1. Fig. 6 is a section of the lower roll-mounting of the feeding device on the line zz of Fig. 1, and Fig. 7 is a detail in front elevation of the aperture-closing plates for the casing.

1 represents the frame of the machine, and 2 the casing, through which the stock (shown as a piece of picture-molding and represented at X) is adapted to be caused to pass. The casing may be formed in any suitable manner. I have shown its ends as consisting of plates 3 4, secured to the frame and having lugs 5, through which they are connected by bolts 6, the top of the plates being connected by a spanner-plate 7, secured to the end plates. Side plates 8 9 are hinged to the spanner-plate by hinges 10, handles 11 being provided for raising the side plates, and thereby exposing the interior of the casing for inspection or adjustment and attention of the parts. The casing is preferably provided with glass inclosing frames 12 in the side plates through which the operation of the device may be observed, the frames being hinged on hinges 13 for access to the interior of the casing, a catch 14 holding the frames closed.

Preferably at each side of the frame of the machine there are one or more receptacles 15, suitably placed, adapted to contain the composition or material with which it is desired to coat the stock. I have shown three of these receptacles at each side of the frame, although it is obvious that any suitable number may be employed, dependent on the various kinds of material it is desired to use in coating or finishing.

A suitable number of atomizers 16 are arranged, preferably, at each side of the machine. These atomizers are preferably mounted on posts 17, taking into apertures 18 in the frame and adjustable therein to height and about the axis of the posts, and secured in adjusted position by means of bolts 19. Each of the posts supports a shelf 20, having a plate 21 adjustable thereon, as by a bolt 22, taking through a slot 23 in the plate and into threaded apertures 24 24' at the respective ends of the shelf. The shelf is preferably overhanging, with the plate arranged to be secured to the post end or overhanging end of the shelf for regulating the overhanging of the atomizer-head. The plate has a trunnion 25 thereon, about which a nozzle-support 26,

forming an atomizer-head, is adapted to be adjustably clamped in suitable manner. The atomizer-head comprises two branches 27-28. A coating-conducting tube 29 is adjustably secured in the branch 27, as by being shifted longitudinally in an aperture therein and secured in place by a set-bolt 30. A compressed-air or blast conducting tube 31 is longitudinally adjustable in the branch 28, as by passing through an aperture therein, and secured in adjusted position by a set-bolt 32. The tubes 29, 31 are respectively provided with removable tips 33, 34, the longitudinal adjustment of the tubes permitting the orifices 15 in the ends of the tips to be placed in relatively suitable positions for creating the proper spray and the adjustment of the head 20 permitting the spray to be projected in suitable direction for proper application to the stock.

35 is a pressure-tank into which compressed air or other pressure medium may be introduced through a pipe 36, a cock 36' shutting off power to all atomizers, flexible tubes or 25 pipes 37 connecting the tubes 31 with the interior of the pressure-tank, suitable cocks 38 being provided for regulating the passage of pressure to the various tubes 31 or entirely cutting them off selectively, as may be desired. Providing the pressure-tank from 30 which the various tubes are fed insures uniformity of pressure to all the pipes.

The receptacles 15 have pipes 39 taking into them and projecting almost to the bottom 35 thereof, the pipes 39 communicating with the respective tubes 29, preferably by a flexible connection 40. The pipes 39 are supported in covers 41. Each of the receptacles is also provided with a cock 42 for emptying the receptacle when desired.

The material with which it is desired to coat the stock usually consists of mixtures whose ingredients have different specific gravities, and in order to preserve the ingredients in 45 properly-mixed state and convey the same properly mixed through the atomizers I form connection between the pressure-tank 35 and the receptacles for conducting the fluid under pressure from the pressure-tank into the material contained in the receptacles, as by means 50 of a pipe 43, communicating with the interior of the pressure-tank and having branches 44 taking into the several receptacles and communicating with pipes 45, preferably located 55 at the bottoms of the receptacles, the pipes 45 being provided with apertures through which air or fluid under pressure is caused to pass into the material in the receptacles for agitating the same. A suitable stop-cock 46 60 may be provided in each of the branches, and a stop-cock 47 may be provided in the pipe 43.

There are preferably a plurality of atomizers arranged in succession on each side of the path of travel of the stock with a plurality 65 of receptacles at each side of the path of

travel of stock and arranged so that the feed of each atomizer may be regulated or entirely discontinued, if desired. In my improved device stock of various kinds may be passed through the machine for receiving its finish— 70 i. e., being coated with various substances which it may be desired to apply to it— whether such coating or finish be applied direct to the stock or be an intermediate or final coat. Thus my improved device may be 75 employed in applying shellac, varnish, bronze, or various materials with which it is desired to cover the stock.

For passing the stock through the casing of the machine I prefer to mount the feeding 80 agency outside the casing at the feeding-in end of the machine. Thus in the present exemplification of my invention I show a feeding-in table 51, in which a lower roll 52 is supported, as on a shaft 53, having concentric studs 54, 55 and an eccentric journal 56 for the roll, the concentric studs being mounted, respectively, in bearings 57, 58 in the table, the shaft being rigidly held by a nut 60, clamping the shaft to the table. When the 90 shaft is turned, the eccentric mounting of the roll causes the roll to project more or less above the table.

61, 62 are standards extending above the table and secured to the table-frame. A shaft 95 63 is secured in the standards in bearings 64, 65. A gear 66 is journaled on the shaft and is held against endwise movement thereon between the bearing 65 and a collar 59, secured to the shaft. The gear has an elongated hub 100 67, to which is secured an operating device, as a pulley 68.

69 is a yoke journaled in bearings 70, 71 on stud-journals 72, 73 of the bearings 64, 65. The gear 66 meshes a gear 74, journaled on a stud 105 75 on the yoke. The gear 74 meshes an operating-gear 76, secured to a feed-roll shaft 77, journaled in bearings 78, 79 of the yoke 69. The feed-roll shaft carries a feed-roll 80, suitably secured thereto and adjustable thereon, this feed-roll being preferably a cushion feed-roll, the feeding-body of the roll being preferably composed of rubber. For accommodating different thicknesses of stock the yoke has a link 81, pivotally secured thereto at each 110 side thereof, each of the links having a bolt 83, taking through a slot 84 therein and into the table-frame for positioning the upper feed-roll relatively to the table.

The end walls of the casing are provided 115 with openings 85, through which the stock passes. The size of the openings may be regulated by having a side plate 86 at either side of the opening adjustably secured to the end wall of the casing by having a bolt 87 pass 120 through a slot 88 in the plate. An upper plate 89 may also be provided, being adjustable by having bolts 90 take through slots 91 in the plate 89 and into the end wall of the casing. A plate 92 takes under the plate 89. 130

In employing various kinds of coating for the stock dust is created inside of the casing. For removing dust I provide, preferably, each end of the casing with an opening 93, with each of which a pipe 94, in which there may be a damper 94', communicating with an exhausting device, such as a fan-blower 95, connects for drawing off excessive dust, care being taken, however, to avoid counter-currents detrimental to the application of the coating through the atomizers.

In order to guide the stock, I provide the feeding-in table with side gages 96 96', adjustable laterally on the table by means of **T**-bolts 97, passing through slots 97' in the gages and into **T**-slots 98 in the table and held in place by nuts 99. These gages guide the stock into the machine and the stock is fed through the machine preferably by having the following piece of stock take against the preceding piece and pushing it through. In my improved device I have provided the feeding agency outside the casing, so that the finish on the stock may not be injured by devices contacting therewith after application of the coating. If desired, the table inside the casing may consist of a ridge-plate 100, having ridges 101, upon which the stock may ride. In practice many of the compositions for coating are composed of viscous substances liable to offer resistance to the passage of the stock through the casing if the stock take directly against a plane table and the table receive a coating of the substance. In order to reduce this resistance to the minimum, I have provided the ridges 101 in the table. A feeding-out table 102 may also be provided and preferably have the ridges thereon.

In my improved device compositions of different substances, colors, or kinds may be employed in the various receptacles for producing various and different effects at one operation or passage of the stock through the machine, or the atomizers near the feeding-in end of the casing may be employed for providing the stock with a coarser or under coating, while those near the feeding-out end may provide a final or finishing coating at one passage of the stock through the machine, whereby passages of the stock through the machine may be saved. In my improved device also the atomizers may be angled with relation to each other and pointed toward the stock from various heights and directions (see exemplification in the drawings) for proper application of the various coatings to the various parts of the stock in the passage of the latter through the machine.

Having thus fully described my invention, what I claim as new, and desire to secure by Letters Patent, is—

1. In a machine of the character described, the combination of a casing, means for feeding stock through said casing, an atomizing

device for applying coating to said stock inside said casing while passing through said casing, and means for adjusting said atomizing device to height and angle and securing the same in adjusted positions. 65

2. In a device of the character described, the combination of a casing, a feeding device outside said casing for feeding the stock through said casing, an atomizing device for applying coating to said stock in said casing while passing through said casing, and means for adjusting said atomizing device to height and angle and securing the same in adjusted positions. 75

3. In a device of the character described, the combination of a casing, feeding and guiding devices outside said casing for feeding stock through said casing and coating the same therein, an atomizing device for coating said stock while passing through said casing, and means for adjusting said atomizing device to height and angle and securing the same in adjusted positions. 80 85

4. In a molding-finishing machine, the combination of a casing through which the molding is arranged to pass, a plurality of atomizers in said casing for said molding, means for separately adjusting said atomizers to height and angle and separately securing the same in adjusted positions, and a feeding device for said molding, substantially as described. 90 95

5. In a molding-finishing machine, the combination of a casing through which the molding is arranged to pass, a plurality of atomizers in said casing for said molding, means for separately adjusting the angles of said atomizers, a plurality of receptacles for feeding said atomizers, and a feeding device for said molding, substantially as described. 100

6. In a coating-machine, the combination of a casing, a table therein, atomizers arranged at both sides of said table, means for passing stock through said casing on said table between said atomizers. 105

7. In a coating-machine, the combination of a casing, a table therein, atomizers at both sides of said table for spraying the stock upon said table while being fed through said casing, a pressure-tank, a pressure-passage for each of said atomizers from said pressure-tank, and a regulating-cock in each of said passages. 110 115

8. In a coating-machine, the combination of a casing, a table therein, a plurality of series of atomizers in said casing at each side of said table, and a material receptacle for each of said series, whereby different material may be supplied to each of said series of atomizers, and feeding mechanism for said stock. 120

9. In a coating-machine, the combination of a casing, a ribbed table therein, means for feeding stock on said table through said casing, a plurality of atomizers in said casing at

each side of said table, a pressure-tank, a composition - receptacle for said atomizers, and flexible connections between said respective atomizers and said pressure-tank and receptacle, substantially as described.

10. In a coating-machine, the combination of a casing having an opening at each end through which stock is arranged to pass, means for regulating the size of each of said openings, an atomizer in said casing for spraying stock passing therethrough, means for adjusting said atomizer to height and angle and securing the same in adjusted positions, and a feeding device outside said casing for feeding 15 said stock.

11. In a coating-machine, the combination of a stock-supporting table, atomizing apparatus arranged at both sides of said table, means for adjusting said atomizing apparatus to 20 height and angle and securing the same in adjusted positions, and means for feeding stock between said atomizing apparatuses.

12. In a coating-machine, the combination of a stock-supporting table, atomizers at both 25 sides of said table, means for adjusting said atomizers to height and angle with relation to said table, and means for feeding stock longitudinally of said table between said atomizers.

13. In a coating-machine, the combination 30 of a ribbed table, atomizing apparatus at both sides of said table, means for feeding stock on said table between said atomizing apparatuses, and means for regulating the angle of application of said atomizing apparatuses to 35 said stock.

14. In a coating-machine, the combination of a casing through which stock is arranged to pass, said casing having an opening at each end for stock, a ribbed table in said casing for 40 said stock, means for feeding said stock, means regulating the size of said openings, and atomizing apparatus for applying coating to said stock inside said casing while passing through said casing.

45 15. In a coating-machine, the combination of a casing, means for passing stock through said casing, a ribbed table in said casing for said stock, and atomizing apparatus for applying coating to said stock inside said casing 50 while passing through said casing, said casing having observation-opening therein.

16. In a coating-machine, the combination of a stock-supporting table, stock - feeding means, an atomizer-head, a plate on which said 55 head is trunnioned, a post, a shelf thereon,

said plate having adjustable connection with said shelf, substantially as described.

17. In a coating-machine, the combination of a casing, a ribbed feeding-table therein, and an atomizer in said casing arranged to play on 60 stock on said table.

18. In a machine of the character described, the combination of a casing, means for feeding stock through said casing, an atomizing device for supplying coating to said stock inside said casing while passing through said casing, and means for adjusting said atomizing device to height and angle. 65

19. In a molding-finishing machine, the combination of a casing through which the molding is arranged to pass, a plurality of atomizers for applying coating to said molding in said casing while passing through said casing, a pressure-tank for said atomizers, means separately and simultaneously cutting off said 75 atomizers from the pressure in said tank, and means for adjusting said atomizers to angle.

20. In a molding-finishing machine, the combination of a casing, a ribbed table therein for supporting the molding, a plurality of atomizers for supplying coating to said molding in said casing while passing through said casing, a pressure-tank for said atomizers, means separately and simultaneously cutting off said atomizers from the pressure of said tank, 85 means for adjusting said atomizers to angle, and a feeding device for said molding, substantially as described.

21. In a molding-finishing machine, the combination of a casing, means for feeding molding through said casing, an atomizing device for supplying coating to said molding inside said casing while passing through said casing, a post for supporting said atomizing device, and means for adjusting said atomizing device 95 to height and angle, substantially as described.

22. In a molding-finishing machine, the combination of a casing, supporting means for said molding in said casing, an atomizing device for supplying coating to said molding inside said casing, and means for adjusting said atomizing device to height and angle. 100

In testimony whereof I have signed my name hereto in the presence of two subscribing witnesses. 105
